UNITED STATES PATENT OFFICE.

ADOLPH ROTHSCHILD, OF ST. LOUIS, MISSOURI, ASSIGNOR TO THE STRAUS CO., OF
ST. LOUIS MISSOURI, A CORPORATION OF MISSOURI.

GOLF OR CADDY BAG.

Application filed September 12, 1921. Serial No. 499,891.

To all whom it may concern:

Be it known that I, ADOLPH ROTHSCHILD,
a citizen of the United States, residing at
the city of St. Louis, State of Missouri, have
5 invented a certain new and useful Improve-
ment in Golf or Caddy Bags, of which the
following is a specification, reference being
had to the accompanying drawing, forming
a part thereof.

10 This invention relates to a certain new and useful improvement in golf or caddy bags, the principal object of my present invention being to provide a bottom or base for golf or caddy bags which may be cheaply and economically manufactured, which is composed of few co-operating separable parts which may be conveniently and inexpensively fastened or secured in operative position to and upon the bag and which may 15 be readily detached from the bag for replacement or renewal, and which is adapted not only to form an efficient support for the golf-clubs placed within the bag, but also to effectively function to retain the normal circular shape of the bag at its base and, by resisting the more or less destructive wear to which the bag in use is especially subjected at its base, durably prolong 20 the life and usefulness of the bag-body.

25

30 With the above and other objects in view,
my present invention resides in the novel
features of form, construction, arrangement,
and combination of parts hereinafter de-
scribed and afterwards pointed out in the
35 claims.

In the accompanying drawing,

Figure 1 is a fragmental elevational view of a golf or caddy bag embodying my invention;

40 Figure 2 is a vertical sectional view of the bag; Figure 3 is an inverted plan view of the

Figure 3 is an inverted plan view of the bag; Figure 4 is a perspective view of the pre-

Figure 4 is a perspective view of the preferred form of the wear-resisting member or ring of the bottom of the bag; and Figures 5 and 6 are inverted plan views

Figures 5 and 6 are inverted plan views of slightly modified forms of bags embodying my invention.

50 Referring now more in detail to the drawing, which illustrates practical embodiments of my invention and in which like reference-

characters refer to like parts throughout the several views, the body 1 of the bag is in the form of an open end cylinder of suitable length and constructed of canvas or other suitable material, as is now customary.

Disposed exteriorly upon the bag-body 1 at its lower end, is a strengthening or reinforcing ring 2 of stiff leather or other suitable material. And disposed interiorly upon the bag-body 1 at its lower end, is a second reinforcing ring 3 likewise of stiff leather or other suitable material, the rings 2 and 3 being riveted, stitched, or otherwise permanently fixed to the bag-body 1 and the interior ring 3 also providing an annular shoulder, as at 4, within, and adjacent the lower end of, the bag, for purposes shortly appearing.

5 The bottom of the bag comprises a disk
of leather, fabric, or other suitable mate-
rial and faced upon its upper side with a
cushioning layer 6 of felt or other relatively 75
soft material. This disk 5 is of a size or
diameter to fit snugly, but removably, with-
in the bag-body 1 to rest upon the shoulder
4 of inner ring 3, as seen in Figure 2. Em-
bedded or otherwise fixed in, and approxi- 80
mately at the axial center of, the bottom
disk 5, and covered by the cushion 6 against
contact with the golf-clubs placed within the
bag, is a relatively small plate 7 having a
threaded seat for the inner end of a secur- 85
ing and clamping bolt 8.

9 indicates what I term the wear-resisting member of the bottom of the bag, which member is in the form of a preferably skeleton ring comprising a plurality of 90 radial spokes 10, preferably three in number, as shown, a central portion or hub 11 suitably apertured, as at 12, for the fastening-bolt 8, and a preferably continuous rim 13 disposed for the most part to one side of 95 the plane of the spokes 10 and recessed from one or its upper side to provide a preferably continuous annular channel 14 having a width throughout to snugly and more or less tightly, but removably, embrace the 100 body-rings 2 and 3 and the interposed edge of the bag-body 1.

In use, the bag-body being constructed as described, a preferably cushioned disk-bot-

tom 5 is positioned within the bag-body to rest upon the annular shoulder 4 provided by the fixed inner body-ring 3. An outer ring 9 is then fitted upon the lower edge of 5 the bag to embrace at its channel 14 the body-rings 2 and 3 and the interposed edge-portion of the bag-body 1, as clearly illustrated in Figure 2. A screw, bolt, or the like 8 is then projected endwise through 10 the hub aperture 12 of ring 9 to seat in the plate 7 and thereby engage the bottom disk 5, such bolt or the like 8, when fully seated, not only rigidly fastening the disk 5 and bottom ring 9 detachably together, but also 15 firmly removably clamping the disk 5 upon the body-ring 3 and the bottom-ring 9 upon the bag-body in bottom-forming position.

The bottom-ring 9, being preferably a one-piece casting of suitable metal, not only 20 re-inforces and braces the bottom-disk 5 to efficiently support and carry the weight and outward pressure of the golf-clubs placed within the bag, but also to retain the normal shape of the bag and to prolong 25 the life and usefulness of the bag by resisting the destructive wear to which the bag is subjected in frequently being dragged on the ground. The bottom as a whole, comprising the disk 5 and outer ring 9, may be 30 conveniently assembled and operatively attached to the bag, the employment of thread-stitches, rivets, or the like for such purpose being entirely obviated, and should it become necessary or desirable at any time 35 to replace the bag-bottom, the disk 5 and ring 9 may be readily detached from the bag on a removal of the securing-bolt 8 and a new bottom inexpensively and easily substituted, a replacement of the bag-body, be- 40 cause of the wearing-out of its bottom, being also entirely obviated.

The modified forms of the bag-bottom shown in Figures 5 and 6 are substantially similar in all respects to the preferred form 45 of the bag-bottom illustrated in Figures 1 to 4, inclusive, except that in Figure 5 the rim of the outer ring is interrupted as shown to include a plurality of spaced arc-shaped annularly aligning channeled por- 50 tions 13', and in Figure 6, the outer ring in- 55 cludes but a pair of radially aligning spokes 10', each formed at its outer end with an arc-shaped channeled member 13'' forming the rim proper of the ring; and I am aware 60 that further changes in the form, construction, arrangement, and combination of the several parts of my new detachable bottom for golf or caddy bags may be made and substituted for those herein shown and de- 65 scribed without departing from the nature and principle of my invention.

Having thus described my invention, what I claim and desire to secure by Letters Patent is:

1. A golf or caddy bag bottom including 65 a disk adapted to removably fit within the body of the bag, a ring channeled at its rim to removably embrace and fit upon the lower edge of the bag-body, and means for detachably securing the disk and ring to- 70 gether.

2. A golf or caddy bag bottom including a disk adapted to fit within the body of the bag, a reinforcing wear-resisting skeleton ring including a plurality of radial spokes 75 and a rim lying to one side of the plane of the spokes and annularly channeled to snugly embrace and fit upon the lower edge of the bag-body, and means for detachably securing the disk and ring together. 80

3. A golf or caddy bag including a tubular body having an interior shoulder adjacent its lower end, in combination with a bottom-disk adapted to removably fit within the body and upon said shoulder, a ring- 85 member channeled at its rim adapted to removably fit upon the lower end of the bag-body, and means for detachably securing the disk and ring-member together and to the bag-body. 90

4. A golf or caddy bag including a tubular body provided interiorly at its lower end with a fixed shoulder-forming ring, in combination with a bottom-disk disposed within the body to rest upon said ring, a re- 95 inforging ring comprising a plurality of radial spokes and a channeled rim fitted upon the body, its channeled rim snugly embracing the lower edge of the bag-body and said shoulder-forming ring, and means en- 100 gaging the bottom disk and the reinforcing ring for detachably fastening the same together and to the body.

5. A golf or caddy bag including a tubular body provided interiorly at its lower 105 end with a fixed shoulder-forming ring, in combination with a bottom-disk disposed within the body to rest upon said ring, a reinforcing ring comprising a plurality of radial spokes and a channeled rim fitted 110 upon the body, its channeled rim snugly embracing the lower edge of the bag-body and said shoulder-forming ring, and means comprising a bolt having engagement only 115 with the reinforcing ring and the disk-bot- 120 tom for detachably fastening the same together and in bottom forming position upon the body.

In testimony whereof, I have signed my name to this specification.

ADOLPH ROTHSCHILD.
